United States Patent Office.

CHARLES S. LORD AND WILLIAM N. WALKER, OF OTTER RIVER,
MASSACHUSETTS.

Design No. 3,223, dated November 3, 1868.

DESIGN FOR A COOK'S STOVE.

The Schedule referred to in these Letters Patent and making part of the same.

To all whom it may concern:

Be it known that we, CHARLES S. LORD and WILLIAM N. WALKER, of Otter River, in the county of Worcester, and State of Massachusetts, have originated a new Design for Cooking-Stoves, of which the following is a full, clear, and exact description, reference being had to the accompanying photograph, making part of this specification, which represents the stove in perspective.

On the sides A are the oven-doors B, one only being shown, which are provided on their edges with a moulding, *a*.

At the inner edge of the moulding, and extending entirely around the door, is a border, *b*, composed of ornamental points, united together at the base.

Within the border *b* is a raised panel, *c*, having a moulded edge, *d*, inside of which is a border, *e*, similar to the border *b*.

In the centre of the panel *c* is an ornament, *f*, composed of an elliptical bulb, set in a diamond-shaped figure, of scroll-work.

The edges of the hearths C D, top, E, and lower portion, G, are moulded, as seen in the photograph.

The door H, around the edge of which is a moulding, *g*, is provided with a border, *h*, similar to that, *b*, on the oven-door, and in the centre is an ornament, *i*.

On the opposite side of the stove, instead of the door H, there is a panel of the same design.

On each side of the stove is a panel, I, with a moulding and border similar to that of the door H, but without a centre ornament.

The front doors, K L, and the doors M N, beneath the hearth C, are each provided with a moulding, border, and centre ornament, similar to those of the door H.

Above the doors K L is a plain panel, P.

Between the door H and the oven-door B is a narrow panel, *k*.

The feet O are ornamented, as seen at *m n*.

On the panel Q, over the doors B and H, is the name of the firm and their place of business, "Lord & Walker, Otter River, Massachusetts," and beneath the oven-door B is the name of the stove, "Pearl."

What we claim as our invention, and desire to secure by Letters Patent, is—

The design for cooking-stoves, as shown and described.

In testimony whereof, we have hereunto set our hands, and affixed our seals, this 17th day of September, 1868.

CHARLES S. LORD. [L. S.]
WILLIAM N. WALKER. [L. S.]
